3,259,360 DISPENSING SPOUT

Richard C. Hug, St. Louis, Mo., assignor to The Clayton Corporation of Delaware, St. Louis, Mo., a corporation of Delaware

Original application Oct. 5, 1962, Ser. No. 228,623, now Patent No. 3,199,150, dated Aug. 10, 1965. Divided and this application Jan. 8, 1965, Ser. No. 432,925
1 Claim. (Cl. 251—303)

This is a division of application Serial No. 228,623, filed October 5, 1962, now Patent No. 3,199,150, issued August 10, 1965.

This invention relates to pressure dispenser valves of the type utilizing a rubber seal mounting member and having a metering flow orifice.

In such valves, it has been conventional to utilize a large diameter hollow in the dispensing spout, and to drill, punch or mold a small lateral metering orifice through the stem into the spout. As applied to those valves which operate by tilting, this is particularly unsatisfactory, for the direction of tilt may determine to what extent the flow of product to be dispensed reaches a metering orifice which may be only partly uncovered from the surrounding rubber seal. Regardless how the valve is to be operated, whether by tilting or pushing down, when a drilled or punched metering orifice is used, an extra shop operation is necessary, which adds to the manufacturing cost.

A purpose of the present invention includes providing an improved metering valving spout whose stem has flow openings so large as to avoid restriction even though only partially opened when tilted in a rubber seal. A further purpose is to provide for cleaning out material which may clog its metering orifice.

The present invention, as it relates to the valving spout member, consists generally in providing a valving spout with a large lateral flow passage having a top wall penetrated by a needle-thin metering bore which leads upward into the center of the spout, and having a bottom wall including a needle-thin blind clean-out recess in registration with the metering bore.

In the accompanying drawings:

FIGURE 1 is a side elevation of the valve stem, assembled with cooperating valve members shown in section. FIGURE 2 is a sectional view taken along line 2—2 of FIGURE 1.

The type of valving assembly with which the present invention is advantageously utilized is shown in FIGURE 1. The container top member *a* has a central elevated dome *b* including a flat, centrally apertured dome top *c* through whose aperture a valve spout member generally designated *10* projects. Such spout member *10* is mounted in a rubber sealing washer *d* which is clamped against the dome top *c* by the top flange *e* of a plastic molded adaptor or "nipple" *f*, through whose bottom inlet *g* the container contents flow to the valve spout member *10*. A compression spring *h*, based within the adaptor *f* and whose top coil surrounds a bottom guide projection *11* of the spout member *10*, urges it upward and thus restores it to closed, sealed position if tilted or depressed.

The valve spout member *10* is formed integrally by molding plastic material of sufficient rigidity to permit such tilting or depressing. Except for its ports *15* and the lateral flow passage *17* which they form, the member *10* is generally symmetrical about its axis *x—x*. It includes, as its upper portion, a tubular stem *12* which serves as a dispensing spout, whose outer wall may include an enlarged lower cylindrical portion *13*, preferably molded without any parting line. Below the wall portion *13*, the valve spout member *10* has an inward groove *14* interrupted by two relatively large, oppositely disposed flow

2

openings or ports *15* having side walls *16* which may taper inward slightly as shown for purposes of molding. The two flow openings *15* joined at the center of the valve spout member *10* to provide together a lateral flow passage *17*, having a bottom wall *18* and a top wall *19*.

The bottom wall *18* marks the upper imperforate end of a valve head portion *20* which is of substantially larger diameter than the lower cylindrical portion *13*, and seats against the under surface of the sealing washer *d*.

The tubular stem *12* has an outlet bore *21* extending along the axis *x—x* from its upper end down to a level somewhat above the lateral flow passage top wall *19*. Thence inwardly, there is provided a tapering bore portion *22* which narrows to a metering bore *23* immediately above the level of the flow passage top wall *19*. The metering bore *23* provides flow communication from the lateral flow passage *17* to the outlet bore *21*. The cross-sectional area of the metering bore *23* may be needle-thin, while the flow openings *15* are of much greater area. This fact, plus flow communication by means of the groove *14* when the valve spout member *10* is tilted, results in full flow to the metering bore *23*, unaffected by degree or direction of tilt. This result is in contrast to prior constructions in which a single metering orifice through the side wall of a stem, whether formed by molding or drilling, might be only partially uncovered on tilting, resulting in reduced rate of flow through the orifice.

The bottom wall *18* of the flow passage *17* has a blind clean-out recess or depression *24* in registration with the metering bore *23* along the axis *x—x*. The recess *24* has an upper bore portion *25* whose diameter is no greater than that of the needle-thin metering bore *23*; and from its upper bore portion *25* it tapers to a pointed recess bottom *26*.

Should anything clog the metering bore *23*, such clogging is readily relieved by pressing an ordinary needle axially inward into the outlet bore *21*. Such needle's tip will be guided by the tapering bore portion *22* to and through the metering bore *23*, and it will press the clogging material axially downward. Material not broken up or reoriented may be packed into the tapering bore *26* of the clean-out recess *24*. For clean-out purposes, therefore, a needle will be chosen whose diameter is smaller than the metering bore *23*.

The valve here described is suitable for a variety of purposes, some of which may involve affixing to the tip of the spout member *10*, a supplementary actuator or sprayhead including a passage whose diameter may be less than that of the outlet bore *21*. In the claim the term "outlet bore" refers to the outlet bore of the stem *21* and not to any such supplementary member.

Minor modifications which will be apparent to those familiar with the art, and within the scope of the claim, are included herein; and the present invention is not to be construed narrowly, but rather as fully coextensive with the claim.

I claim:

As part of a pressure dispenser valve of the type utilizing a rubber seal mounting member,
a valving spout member including
a valve head portion,
a stem portion outwardly of the head portion, said stem portion having
a lateral flow passage connecting a plurality of flow openings and having a bottom wall and a top wall, the stem portion further having a needle-thin metering bore into substantially the center of the flow passage top wall forming a constriction at the center of the stem, and an outlet bore of greater diameter than the metering bore communicating therewith, and leading outwardly through the spout member,
said flow passage and each of its flow openings being of

greater cross-sectional area, when measured across the path of flow, than the metering bore, and its bottom and top walls being of substantially greater width than the diameter of said bore,
 the bottom wall of the lateral flow passage having a blind clean-out recess in registration with said metering bore,
 said clean-out recess having a diameter no greater than that of a metering bore.
